ORNAMENTAL DESIGN FOR A COMBINED RABBIT FIGURE AND TRICYCLE TOY

Esther Lee Singleton, R.R. 1, Box 52,
St. Anne, Ill. 60964

Filed July 28, 1972, Ser. No. 276,053

Term of patent 14 years

Int. Cl. D21—01
U.S. Cl. D34—15 AN

FIG. 2

FIG. 1 is a side elevational view of an ornamental design for a combined rabbit figure and tricycle toy showing my new design, the opposite side being substantially similar to that shown; and

FIG. 2 is a top plan view thereof.

I claim:

The ornamental design for a combined rabbit figure and tricycle toy, as shown and described.
